[57] CLAIM

The ornamental design for water squirting ball point pen, as shown and described.

DESCRIPTION

FIG. 1 is a left side elevational view of a water squirting ball point pen embodying my new design with its barrel fully extended and with its removable thimble in place over the pen point;

FIG. 2 is a front elevational view thereof;

FIG. 3 is a right side elevational view thereof;

FIG. 4 is a rear elevational view thereof;
FIG. 5 is a left side elevational view thereof the barrel fully retracted;

FIG. 6 is a front elevational view of FIG. 5;

FIG. 7 is a rear elevational view thereof;

FIG. 8 is a top plan view thereof;

FIG. 9 is a bottom plan view thereof;

FIG. 10 is a left side elevational view of the water squirting ball point pen with the barrel fully extended and with the removable thimble applied to the top end;

FIG. 11 is a front elevational view thereof;

FIG. 12 is a right side elevational view thereof;

FIG. 13 is a rear elevational view thereof;

FIG. 14 is a left side elevational view thereof with the barrel fully retracted;

FIG. 15 is a front elevational view of FIG. 14;

FIG. 16 is a rear elevational view thereof;

FIG. 17 is a top plan view thereof; and

FIG. 18 is a bottom plan view thereof.

A view taken from the right side of the same when in the position shown in FIG. 5 is a mirror image of FIG. 5.
